CLAIM

The ornamental design for a hyper inflation bag attached to a manometer, as shown and described.

DESCRIPTION

FIG. 1 is a front elevational view of the hyper inflation bag attached to a manometer;

FIG. 2 is a rear elevational view thereof;

FIG. 3 is a left side elevational view thereof;

FIG. 4 is a right elevational view thereof;

FIG. 5 is a top plan view thereof; and,

FIG. 6 is a bottom plan view thereof.

No part of the phantom lines in the FIGS. form any part of the invention.
